Primary Examiner — Ania Aman(74) *Attorney, Agent, or Firm* — Eversheds Sutherland (US) LLP(57) **CLAIM**

The ornamental design for an injector holder of fuel rail for gasoline direct-injection engine, as shown and described.

DESCRIPTION

FIG. 1 is a front view of an injector holder of fuel rail for gasoline direct-injection engine showing our new design;

FIG. 2 is a rear view thereof;

FIG. 3 is a right side view thereof;

FIG. 4 is a left side view thereof;

FIG. 5 is a top view thereof;

FIG. 6 is a bottom view thereof;

FIG. 7 is a front view thereof with section lines;

FIG. 8 is a cross-sectional view along line 8-8 of FIG. 7; and,

FIG. 9 is a cross-sectional view along line 9-9 of FIG. 7. The dashed broken line showing is included for the purpose of illustrating portions of the article that form no part of the claim.
